UNITED STATES PATENT OFFICE.

RETTA M. COOPER, OF DAVID CITY, NEBRASKA.

DESIGN FOR A HOLDER FOR KNIVES, FORKS, &c.

SPECIFICATION forming part of Design No. 23,131, dated March 20, 1894.

Application filed February 23, 1894. Serial No. 501,312. Term of patent 14 years.

To all whom it may concern:

Be it known that I, RETTA M. COOPER, a citizen of the United States, residing at David City, in the county of Butler and State of Nebraska, have invented a new and original Design for Knife, Fork, and Spoon Holders, of which the following is a specification.

The invention relates to a new and original design for knife, fork, and spoon holders.

10 The object of the present invention is to provide an ornamental and attractive holder designed to be placed on a table in close proximity to a plate for supporting a knife, fork and spoon; and the essential feature resides 15 in a holder comprising similar sides and a horizontally disposed centrally arranged connecting bar, the sides each consisting of a horizontal cross-piece having straight upper and lower edges and similar upper and lower arms 20 and legs arranged in pairs and being outwardly curved, the legs having the edges at their outer ends straight and the corresponding edges of the arms being rounded.

The figure of the drawing is a perspective 25 view of a knife, fork and spoon holder showing my original design.

Referring to the drawing, 1—1 designate

the sides and 2 the horizontally disposed centrally arranged connecting bar for receiving the blade of a knife and tines of a fork. Each 20 side consists of a central portion or cross-piece 3, upward extending arms 4, and depending legs 5; the arms and legs are arranged in pairs and are similarly curved outward. The edges 6 at the outer ends of the 35 legs are straight, and the corresponding edges 7 of the arms 4 are rounded. The upper and lower edges of the cross piece 3 are straight and the upper edges 8 of the sides 1 are for supporting a spoon.

It will be seen that the knife, fork, and spoon holder presents an appearance which is ornamental and attractive.

What I claim is—

The design for a knife, fork and spoon holder, substantially as shown and described. 45

In testimony that I claim the foregoing as my own I have hereto affixed my signature in the presence of two witnesses.

RETTA M. COOPER.
